LOCKING MECHANISM OF SPRING PRO- JECTED LATCHING BOLT TYPE

Edward W. Johnston, Milwaukee, Wis., assignor
to Frank Klinger and Edward W. Johnston,
copartners, doing business as Jay Tool & Mfg.
Co., Milwaukee, Wis.

Application September 4, 1947, Serial No. 772,129

2 Claims. (Cl. 292—74)

1

This invention relates to improvements in latching and locking mechanisms for swinging doors of the spring-projected latching bolt type and particularly rim-type locking latches.

Rim-type latches presently used on the inside of outwardly swinging doors, such as screen doors or storm doors, require, in the installation thereof of carpentry work such as routing out the door jamb to inset the keeper. Latches which may be installed without such carpentry work have only the friction latching feature and are not positively lockable.

It is an object of this invention, therefore, to provide a latching and locking mechanism which may be applied to the inside of outwardly swinging doors without such carpentry work.

A further object is to provide a locking latch which is light in weight, is capable of being inexpensively manufactured, and is of neat and pleasant appearance.

These objects are obtained by providing a keeper which is secured to the surface of the door jamb and a spring-projected latching bolt which is secured to the inner surface of the stile of the door. The keeper has a cupped portion which receives and engages the end of the latching bolt. The cupped portion has sloping inner and outer walls on which the end of the latch bolt rides upon entering or leaving the cup. The latching bolt when extended is rotatable to a locked position, preventing the end from being withdrawn from the cupped portion of the keeper. The locking mechanism is simply installed. With the door closed, the keeper is positioned on the face of the jamb so that its edge is adjacent the stile of the door when closed and then wood screws are inserted to secure it. Next, the latching bolt is positioned on the inner surface of the stile of the door so that its head (as projected) rests snugly in the cupped portion of the keeper. It is then secured by screws. In the ordinary latching of the door the end of the latching bolt rides up the sloping inner and outer surfaces of the cupped portion against spring tension. This tension is sufficient to hold the door closed against forces of gravity, drafts, wind, etc. However, it will readily unlatch under manual force applied to the door. When the latching bolt is rotated to locked position, it cannot be withdrawn and will stay seated in the cup holding the door locked unless abnormal force sufficient to break or deform the latch door is applied.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawing, in which:

Fig. 1 is a view in side elevation of a latching

2

and locking mechanism embodying the present invention;

Fig. 2 is a view in end elevation of the mechanism viewed in Fig. 1 taken from the left-hand end of such figure;

Fig. 3 is a sectional view taken on the line 3—3 of Fig. 1;

Fig. 4 is an exploded view showing the elements of the mechanism viewed in Fig. 1; and

Fig. 5 is a plan view of a proposed blank from which the latching bolt is formed.

Referring to the drawing by reference numerals, the latching and locking mechanism is shown mounted on the inside of an outwardly swinging door such as a screen door or storm door. The keeper 10 is secured to the face of the door jamb J adjacent its door-abutting edge. The keeper is disk-like in shape with a centrally located cup or cupped portion 11 formed therein.

15 In forming the cupped portion 11 its inner and outer walls are sloped at an angle of substantially forty-five degrees to its base plane to provide camming surfaces up and down which the end of the latching bolt may slide in the latching and unlatching action. While it is not necessary, it has been found advantageous to provide the keeper 10 with a chord-like straight edge 12 which provides a guide for properly positioning the keeper adjacent the edge of the jamb and permits the center of the cupped portion to be nearer to such edge. The base of the keeper has holes 13 through which the wood screws 14 are inserted to fasten the keeper in place.

20 The latching bolt 16 is mounted on the inner face of the stile S of the door so that it projects toward the face of the jamb J when the door is closed. A bracket 21 provided with a barrel-like bearing 22 provides the support for the latching bolt 16. The bracket 21 has screw-holes 24

25 in its four corners through which the wood screws 25 are inserted to secure the bracket in place. The latching bolt 16 is hollow and is preferably formed from a single blank 17 shaped as generally shown in Fig. 5. The blank 17 has a

30 tab 18 and complementary notches 19 shaped and placed as shown. The latching bolt is formed by folding the blank about its central axis and at the same time curving the surfaces to make the blank cylindrical in form. When

35 the blank is formed the notches complement each other to form a pair of oppositely positioned L-shaped slots 19, and the central portion provides a semi-spherical head 20. At the time

40 the blank 17 is formed the tab 18 is bent at right angles to the plane of the blank and twisted through ninety degrees, thereby presenting a flat surfaced handle which is readily usable for rotating the latching bolt. In the forming process, the edges of the blank 17 are upset and make a circumferential flange 30 designed to abut against the bearing 22 and limit the forward movement of the latching bolt 16. The latching bolt 17 has a slidably fit within the bearing 22

and is resiliently continually urged toward latching position by a coil compression spring 26. The coil compression spring 26 is carried within the bolt 16 with one end reacting against the inside of the head 20 and the other end reacting against a disk 27 loosely mounted within the bolt 16 and held by a pin 28 rigidly mounted in apertures 23 formed in the bearing 22. The pin 28 passes through the L-shaped slots 19. The base of the L is so spaced from the flange 30 and the apertures 23 are so spaced from the inner edge of the bearing 22 that when the bolt 17 is projected the full amount the limiting abutment will be between the flange 30 and the end of the bearing 22 and there will be a slight space between the pin 28 and base of the L-shaped slots 19. The purpose of this is to have the wear take place between the flange and the bearing, which provides a large bearing area, rather than between the pin 28 and the base of the L-shaped slots 19. The legs of the slots 19 are long enough to permit the latching bolt 16 to be withdrawn against the compression of the spring far enough to permit its end 20 to ride up the walls of the cupped portion 11. As most clearly shown in Fig. 1, the L-shaped slots 19 are so positioned angularly circumferentially of the bolt 16 that when the locking handle 18 is horizontal, the pin 28 will be in alignment with the legs of the slots 19 and thus permit the barrel to be withdrawn. However, when the handle 18 is depressed, the latching bolt 16 is rotated clockwise as viewed in Fig. 2. This brings the base of the L-shaped slots 19 into alignment with the pin 28. When in this position the pin 28 will engage the bases of these slots and prevent the latching bolt 16 from being withdrawn. Any conventional and conveniently installed door handle 29 may be secured to the outside of the stile S.

To install the latching and locking mechanism, the keeper 10 is first positioned on the face of the jamb J with its guiding edge 12 parallel to and substantially in alignment with the door abutting edge of the jamb. While held in this position the screws 14 are driven. With the door closed the latching bolt 16 (while unlocked and projecting) is then placed on the inner surface of the stile S and positioned so that the head 20 snugly rests in the cupped portion 11. There may be some slight retraction of the bolt 16 in the bearing 22 but this is not necessary if there is a snug engagement between the head 20 and the cup 11. While in this position the screws 25 are driven. It will thus be seen that the installation requires no skilled carpentry work.

The operation of the locking latch is as follows: As the door is swung to closed position, the head 20 strikes against the sloping outer wall of the cupped portion 11 and the camming action therebetween causes the bolt to be withdrawn compressing the spring 26. As the head 20 passes over the top of the wall, the action of the spring 26 causes the head 20 to slide down the inner wall and snap into the cupped portion 11. The tension in the spring 26 is sufficient to hold the latch in this position against the normal forces exerted against the door by wind, drafts, and gravity. However, by manually pressing outwardly against the door near the latching mechanism the head 20 will ride up the inner wall of the cupped portion 11 and cause the bolt to be withdrawn against the tension of the spring 26 permitting the door to be opened. However, if it is desired to lock the door, the bolt 19 is rotated by depressing the locking handle

18. This brings the base of the L-shaped slots 19 into alignment with the pin 28 to prevent the latching bolt 16 from being withdrawn under the camming action set up by force applied to open the door.

It should be noted that the various parts of the locking mechanism may be inexpensively stamped from sheet metal and yet when assembled these parts are compact, accurate, and neat appearing. The keeper 10 does not unduly project from the base of the jamb J and has no sharp projections obstructing passage through the doorway.

Although only one embodiment of the invention is shown and described herein, it will be understood that this application is intended to cover such changes or modifications as come within the spirit of the invention or scope of the following claims.

I claim:

1. A latch for the inside of outwardly swinging doors comprising a bearing bracket having a bearing for a latching bolt adapted to be directly secured to the inner face of a door stile adjacent the door jamb, a hollow latching bolt slidably mounted in said bearing, said bolt having a semi-spherical keeper engaging head, a pair of oppositely related L-shaped slots in the wall of said bolt, a pin mounted in said bearing and passing

30 through said slots, a spring mounted within said bolt and reacting between said head and said pin to resiliently urge said bolt into latching position, the legs of said L-shaped slots permitting operative longitudinal movement of said bolt 35 relative to said bearing, a handle on said bolt whereby said bolt may be rotated when in extended position, the base of said L-shaped slots cooperating with said pin when said bolt is rotated to one extreme of rotation to restrain said bolt from longitudinal withdrawing movement.

2. A door latch comprising a bracket adapted to be secured to the surface of a door stile, a latching bolt bearing carried by said bracket, a hollow latching bolt slidably mounted in said bearing, said bolt having an outer closed end adapted to engage with a keeper, the other end of said bolt being open, a pair of oppositely related slots in the wall of said bolt for slidably accommodating a pin, a pin mounted in said bearing and passing through said slots to permit said bolt to have longitudinal movement, a spring mounted within said bolt and reacting between said closed end and said pin to resiliently urge said bolt forwardly into keeper-engaging position, and a flange at the open end of said bolt engageable with said bearing to limit the forward movement of said bolt.

EDWARD W. JOHNSTON.
